UNITED STATES PATENT OFFICE

ARTHUR F. WALKERDINE, OF SAN FRANCISCO, CALIFORNIA

DESIGN FOR A FERNERY

Application filed February 10, 1930. Serial No. 34,471. Term of patent 7 years.

To all whom it may concern:

Be it known that I, ARTHUR F. WALKERDINE, a citizen of the United States, residing in the city and county of San Francisco, State of California, have invented a new, original and ornamental Design for a Fernery, of which the following is a specification, reference being had to the accompanying drawing, forming a part thereof.

Figs. 1 and 2 are front and end elevations, respectively, of a fernery showing my new design.

The opposite back and end elevations of the fernery are similar in design and ornamentation.

I claim:

The ornamental design for a fernery as shown and described.

ARTHUR F. WALKERDINE.
